US00D763938S

(12) **United States Design Patent**
Muehlemann et al.

(10) **Patent No.:** **US D763,938 S**
(45) **Date of Patent:** **** Aug. 16, 2016**

(54) **OPTICAL SENSOR ARRAY**

(71) Applicant: **Cephalogics, LLC**, Boston, MA (US)

(72) Inventors: **Thomas Muehlemann**, Zurich (CH); **Catherine Pace**, Lausanne (CH); **Karim Haroud**, Chavannes sur Moudon (CH); **Stefan Troller**, Sissach (CH); **Azadeh Khanicheh**, Wakefield, MA (US); **Michel Bruehwiler**, Newton, MA (US); **Russell L. Herrig**, Lexington, MA (US); **Jeffery J. Caputo**, Winchester, MA (US)

(73) Assignee: **Cephalogics, LLC**, Boston, MA (US)

(**) Term: **14 Years**

(21) Appl. No.: **29/486,801**

(22) Filed: **Apr. 2, 2014**

(51) LOC (10) Cl. **24-01**

(52) U.S. Cl.

(57) **CLAIM**

The ornamental design for an optical sensor array, as shown and described.

DESCRIPTION

FIG. 1 is a front, right perspective view of the optical sensor array;

FIG. 2 is a front view of FIG. 1;

FIG. 3 is a back view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1;

FIG. 8 is a front, left perspective view of FIG. 1; and,

FIG. 9 is a back perspective view of FIG. 1.

The evenly spaced dashed lines depict unclaimed environment. Features shown in dashed-dot lines, such as appears, for example, in FIGS. 3 and 9, represent boundary lines.
